ELECTRON TUBE SOCKET

Vincent E. Thomson, Garden City, N. Y., assignor
to The Sperry Corporation, a corporation of
Delaware

Application November 4, 1944, Serial No. 581,972

2 Claims. (CL 173—328)

1

This invention relates to an improved socket for an electron tube or the like, and more particularly to a socket especially adapted for relatively large or heavy electron tubes requiring accurate positioning.

In the past, most electron tubes have been provided with a base fitted with pronged terminals and a socket adapted to receive these terminals has been employed simultaneously to make electrical contact therewith and to provide physical support for the tube itself. As the size and weight of the electron tube increased, and as the requirements for accurate positioning of the tube with respect to the apparatus with which it was to be used became more stringent, such simple mounting means became inadequate.

It is an object of the present invention, therefore, to provide an improved socket for an electron tube or the like in which the means for securing electrical connection with the terminals of the tube are separate from the means for physically supporting it.

Another object of the invention is to provide a socket adapted securely to support a tube without introducing any mechanical stress upon the terminals of the tube.

A further object is to provide an electron tube socket in which the connector, which is adapted to make electrical connection to the terminals of the tube, is supported with respect to the independent mounting means for the tube during insertion and withdrawal of the tube from the socket, but floats with respect to the mounting means when the tube is being supported thereby.

The above and other objects of the invention will be better understood by reference to the following description taken in connection with the accompanying drawings, in which like reference numerals designate like components and in which:

Fig. 1 is a perspective view of a socket in accordance with the present invention, together with an electron tube adapted to be inserted therein;

Fig. 2 is an elevation, partly in section, of the socket and of a portion of the tube of Fig. 1, the relative positions of which are those assumed when the operation of inserting the tube in the socket is begun;

Fig. 3 is a section taken on the line 3—3 of Fig. 2;

Fig. 4 is a fragmentary plan view, partly in section, of a portion of the structure shown in Figs. 2 and 3;

Fig. 5 is an elevation, partly in section, of the 55

socket and of a portion of the tube shown in Fig. 1, in which the tube is in its second phase of insertion in the socket;

Fig. 6 is a section taken on the line 6—6 of Fig. 5;

Fig. 7 is an elevation, partly in section, of the socket and of a portion of the tube of Fig. 1, in which the tube has assumed its fully inserted and locked position with respect to the socket; and

Fig. 8 is a section taken on the line 8—8 of Fig. 7.

Referring to Fig. 1 of the drawings, there is shown an electron tube 1 which, for example, may be of the Klystron type, having a base 2 connected to the balance of the tube by a seal 3 of glass or the equivalent and bearing the usual pronged terminals 4 and locating pin 5 arranged, for example, in the standard octal configuration. Tube 1 is also provided with a mounting flange 6 located above the glass seal and carrying a plurality of adjustable mounting studs 7 having grooved ends. The rigid assembly of parts 2, 3, 4, 5, 6 and 7 in tube 1 constitutes a specially formed electrical connector plug insofar as their relation to the connector and socket arrangement, to be described, is concerned.

Socket 8 comprises a mounting ring 8 having attached to it a shell 10 which in turn serves as a guide for connector 11 provided with plural tabs 12. Cable 13 is attached to the terminal lugs of connector 11. Shell 10 is provided with a plurality of tabs 14 which receive rivets 15. Fig. 2 shows one of the tabs 12 seated in a notched portion 20 and guides extending therefrom into the larger area of opening 18. The latter rigidly engage mounting ring 8, but slidably engage guide ring 16, which is rotatably disposed within mounting ring 8. Shell 10 is also provided with a plurality of tabs 17, adapted for securing the socket 40 to a chassis 22 (see Figs. 2, 5 and 7) by means of bolts received by threaded inserts 18.

Socket 8 is optionally provided with a helical spring 29, encircling shell 10 and suitably engaging flared portion 30 thereof at its lower end. The upper end of spring 29 engages, and may be secured in any suitable manner to, tabs 12 extending from connector 11. The purpose of spring 29 is to exert a force, both radial and axial, tending to position tabs 12 in notches 28 (Fig. 7), so that connector 11 occupies the position shown in Fig. 1 whenever socket 8 is unoccupied by tube 1. It will be understood that spring 29 may be omitted if desired without departing from the invention. In some cases, for example, cable 13 may be sufficiently stiff to insure that connector 11 remains

at or near the uppermost limit of its travel when the socket is unoccupied by the tube, thus eliminating any necessity for additional positioning means such as spring 28. When the socket is mounted vertically as shown, connector 11 will tend to drop slightly, upon removal of the tube, so that tabs 12 occupy notches 28 (see Fig. 2), without dependence upon the use of spring 28 or upon the stiffness of cable 13.

Fig. 2 shows the electron tube 1 of Fig. 1 partially inserted in socket 8 of Fig. 1. Pronged terminals 4, protruding from the tube base 2, have just been fully engaged by connector 11. This view shows clearly one of the plural openings 19 with which shell 10 is provided. Each of these openings has a notched portion 20 adapted to receive a tab 12 when connector 11 is positioned to receive terminals 4 of tube 1. This view also shows the use of bolts 21 to secure the socket assembly to a chassis or base 22.

Fig. 3 shows more clearly the relative positions of mounting ring 9 and guide ring 16, which is rotatably secured within mounting ring 9 by means of rivets 15, slots 23 being provided in ring 16 to permit its rotation. Guide ring 16 is also provided with holes 24, which in the initial position register with holes 25 (Fig. 4) in mounting ring 9, and which are adapted to receive the grooved ends of mounting studs 7 of electron tube 1. As shown more clearly in Fig. 4, mounting ring 9 is keyhole slotted, cut and bent to form spring members 26, which are adapted to engage and hold, upon a slight clockwise rotation of tube 1, the grooved ends of mounting studs 7.

Referring now to Figs. 5 and 6, it will be noted that tube 1, pronged terminals 4 of which have fully engaged connector 11, has been lifted slightly, rotated clockwise, and lowered until the ends of mounting studs 7 have entered holes 24 in guide ring 16 and holes 25 in mounting ring 9. Each of tabs 12 has left a notched portion 20 of an opening 19 to occupy a new position axially and radially displaced from that shown in Figs. 2 and 3. In Figs. 5 and 6, the tube has been fully inserted in the socket, but is not locked in place.

Figs. 7 and 8 show the tube in its locked position with respect to the socket. It will be noted, especially in Fig. 8, that tube 1 has been further rotated in a clockwise direction, causing guide ring 16 to turn in a clockwise direction with respect to mounting ring 9 and mounting studs 7 to be securely engaged by members 26 of mounting ring 9. Each of tabs 12, attached to connector 11, occupies a position well separated from the edges of an opening 19 in shell 10, and hence connector 11 may be said to be "floating" with respect to the shell, since it is now supported only by the tube. As shown in Figs. 7 and 8, tube 1 is locked in place and its weight is supported entirely by mounting studs 7 which in turn are engaged by mounting ring 9 and hence held in fixed position with respect to chassis 22.

Removal of the tube from its socket is a reverse of the above-outlined steps of insertion, and may be better understood by reference to Figs. 7 and 8. After tube 1 has been rotated sufficiently in a counterclockwise direction to release the ends of mounting studs 7 from spring members 26 of mounting ring 9 (under which condition it will occupy the position with respect to socket 8 which is shown in Figs. 5 and 6), the tube is raised until studs 7 entirely clear holes 24 in guide ring 16, so that it can be rotated still further in a counterclockwise direction until tabs 12 strike walls 27 of openings 19 in shell 10. Slight addi-

tional lifting of tube 1 brings each of tabs 12 into a notched portion 28 in shell 10. Notches 28 provide adequate support for tabs 12 and hence connector 11, both against rotation and against axial movement in a vertical direction, thus permitting pronged terminals 4 of tube 1 to be withdrawn without difficulty from connector 11. If the socket is vertically mounted and spring 28 is omitted, connector 11 tends to drop down until each of tabs 12 occupies a notch 28, so that the socket is ready for the next insertion of the tube.

It will be observed from the above description of one embodiment of the invention that an improved socket is provided which does not require that access be had to both sides of the chassis during insertion or removal of the tube. Shell 10 by means of notches 28 and 28 provides the necessary support and guide for connector 11 respectively during each of these operations. This is one of the features of the present invention.

It will also be observed from the above description that the exact position of connector 11, when tube 1 is in its fully inserted and locked position (as shown in Figs. 7 and 8) is not critical but may vary both axially and in rotation, as well as radially, by appreciable amounts. In practice, this is a highly desirable feature, since it is extremely difficult to base an electron tube, or the like, employing a glass seal with a high degree of precision either as to its axial dimensions or as to the exact rotational orientation of the tube terminals with respect to its mounting flange or internal elements.

While the drawings show and the above description explains the construction of one particular form of socket in accordance with the present invention, it will be understood that numerous modifications may be made without departing from the scope thereof. For example, mounting studs 7 of tube 1 may be made to engage mounting ring 9 otherwise than by rotation, one other method, for instance, being the use of ball-shaped instead of grooved or notched ends of studs 7 with the provision of suitable receiving sockets on mounting ring 9. Another change which may be made from the socket shown would be the use of a terminal configuration on the tube other than the standard octal base, such a variation merely requiring a corresponding change in connector 11. Likewise, although the socket is shown in the drawings as mounted with its axis vertically disposed, it will be understood that it may be operated in any other desired position with equally satisfactory results.

It will also be understood that the exact shape and form of openings 19 in shell 10, together with those of notches 20 and 28, may be altered within wide limits to facilitate manufacture or for other reasons without departing from the scope of the present invention. It is preferable, however, that the relative dimensions be such that the connector can be reached with the tube prongs even if it should accidentally assume its extreme lowermost position prior to the engagement of the prongs by the connector.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope 75 of the invention.

What is claimed is:

1. A socket for a tube having terminals and separate supporting means, comprising a terminal connector for receiving said terminals, a cylindrical sleeve surrounding said connector having a mounting flange thereon for receiving and securing said supporting means upon rotational engagement therebetween, said sleeve having a plurality of helical openings therein each terminating in one end in a seat providing notch, said terminal connector having a plurality of tabs radially extending therefrom, one passing through each of said helical openings, whereby said terminal connector may be positioned by said tabs in said seat to facilitate the engagement of said terminal connector with said terminals, said connector being axially positionable upon rotational engagement of said supporting means with said mounting means by virtue of the relationship of said tabs and said helical openings to thereby free said tabs and said connector from engagement with said sleeve.

2. A socket for a tube having terminals and separate supporting means, comprising a terminal connector for receiving said terminals, a mounting flange for receiving and securing said supporting means upon rotational engagement therebetween, a cylindrical sleeve extending from said mounting flange and surrounding said connector and having a plurality of spiral openings therein each terminating at the flange end of said sleeve in a

5 seat providing notch, said terminal connector having a plurality of tabs extending radially therefrom through each of said spiral openings of said sleeve and positionable in said seat providing notches, and spring means surrounding said sleeve for coercing said tabs to said seated position and toward said flange, whereby said terminal connector may be positioned in said seat to facilitate engagement of said terminal connector with said terminals and upon rotational engagement of said supporting means and said mounting means, the effect of said spring being overcome and said connector being axially positionable by interaction of said tabs on said spiral openings.
